CLAIM

The ornamental design for a cylindrical fixture mount, as shown and described.

DESCRIPTION

FIG. 1 is a front, bottom perspective view of a cylindrical fixture mount showing a first embodiment of our design, which is the same as a rear, bottom perspective view thereof; FIG. 2 is a bottom view thereof;

FIG. 3 is a top view thereof;

FIG. 4 is a right side, front, top perspective view thereof and is the same as a left side, rear, top perspective view thereof; and

FIG. 5 is a left side, front, top perspective view thereof and is the same as a right side, rear, top perspective view thereof.

FIG. 6 is a front, bottom perspective view of a cylindrical fixture mount showing a second embodiment of our design, which is the same as a rear, bottom perspective view thereof;

FIG. 7 is a bottom view thereof;

FIG. 8 is a top view thereof; and,

FIG. 9 is a rear view thereof and is the same as a front view thereof.

The shade lines in the figures show contour and not surface ornamentation. The dashed lines in the figures form no part of the claimed design.

The cylindrical fixture mount of the second embodiment is shown with symbolic breaks in its height, indicated in the figures by break lines. The appearance of any portion of the cylindrical fixture mount between the break lines—including its height—forms no part of the claimed design.
